PREFABRICATED SHELTER OR THE LIKE

Ving Smith, 2 Agar Ave., New Rochelle, N.Y. 10801

Filed Jan. 24, 1966, Ser. No. 745

Term of patent 14 years

(Cl. D13—1)

FIG. 1

The shelter has substantially the same appearance on each of its four sides.

I claim:

The ornamental design for a prefabricated shelter or the like, as shown and described.
